UNITED STATES PATENT OFFICE.

EDMUND GURNEY, OF PORTLAND, OREGON, ASSIGNOR TO P. J. BURNS, OF PORTLAND, OREGON.

BRICK-HANDLING MACHINE.

1,131,507.

Specification of Letters Patent.

Patented Mar. 9, 1915.

Application filed September 19, 1913. Serial No. 790,766.

To all whom it may concern:

Be it known that I, EDMUND GURNEY, a citizen of the United States, residing at Portland, in the county of Multnomah and State of Oregon, have invented certain new and useful Improvements in Brick-Handling Machines, of which the following is a specification.

This invention appertains to brick making machinery and comprises improvements in what are known as brick cutting tables.

The object of the invention has been to devise especially advantageous means for mechanically transferring a series of green or freshly cut brick from the cutting table to a suitable portable pallet upon which the brick may be readily carried off from the machine, either manually or by a suitable conveyer.

20 The invention utilizes certain principles of construction disclosed in my previous application, Serial Number 671,439, filed January 16, 1912, a pallet being utilized upon which the bricks are received, separated and moved, a stop or push board being arranged above the carriage supporting said pallet and being controlled to move in timed relation with respect to the carriage whereby at a predetermined time said stop will sweep 25 the brick from the spreader pallet onto the portable or removable pallet that is carried off with the brick to the point of deposit where the latter are dried.

30 The invention resides particularly in the special means employed to control the operation of said stop or push board, an especially simple and compact arrangement of parts being devised and the action of the push board being rendered positive as well 35 as readily susceptible of variation by adjustment of suitable means.

In the drawings:—Figure 1 is a side elevation of a conventional type of brick cutting table showing the improvements of the 40 invention applied thereto. Fig. 2 is a front elevation illustrating more particularly the guide frame, the stop or push board mounted thereon, and the operating cables connected with the latter. Fig. 3 is a detail view of 45 the trip lever and its arrangement in respect to the platen or bed of the cutting table which latter is movable with the carriage that controls the operation of the cutting mechanism, dotted lines showing the range of

movement of the trip lever. Fig. 4 is a fragmentary view showing more clearly the relative arrangement of the trip lever and the co-operating co-axially mounted tripping arm. Fig. 5 is a detail view of the trip lever alone.

The cutting table illustrated in the drawings is of a conventional type and while the invention is shown as applied thereto it is to be understood that by reason of the special construction of the various parts of the invention, the latter is adapted to be just as readily attached to and used in connection with many other types of cutting tables.

The numerals 1 denote the sides of the frame of the cutting table, and 2 designates a sliding carriage supported by suitable rollers 3 mounted on shafts 4 journaled in the frame in any suitable manner. The carriage 2 comprises a bed or platen 5 at one end of the same which is movable with the carriage as the latter is actuated back and forth in the operation of the machine. The means for operating the carriage 2 consists of a hand lever 6 mounted on an end of a shaft 7 which is journaled in the frame 1 of the machine and on which is fixed a pair 75 of grooved segments 8. Cables 9 are attached at their outer ends to each side of the carriage 2 and at their inner ends to the adjacent one of the segments 8 and operate around the grooved portion of said segment, 80 any lost motion being readily taken up by adjustment of nuts forming parts of the connections between the cables and the carriage.

Cutting mechanism comprising a cutter frame consisting of the curved arms 10 is 90 pivotally supported upon the frame 1 of the machine and adapted to be given an oscillatory movement under the action of the carriage 2, the range of movement of the arms 10 being illustrated by the full and 95 dotted lines in Fig. 1. The arms 10 are connected by a tension bar 11 with which the cutting wires 12 are connected by suitable tension nuts. An abutment 13 is supported by the frame of the machine and performs 100 its customary function, as will be later described.

All of the construction just set forth is found in the conventional type of machine or cutting table with which my improvements are employed.

The present improvements reside in the provision of attaching parts including sup-

porting arms 14 which are secured to the sides of the carriage 2 in any suitable manner. The arms 14 support near their inner ends a spreader pallet 15 of the kind fully described in my previous application above identified and which, not forming a part of the present invention, is not therefore described in detail. Said arms 14 are also adapted to support a portable or removable 10 pallet 16 adapted to rest on the outer end portions of the arms and spaced from the pallet 15, there being a base board 17 that connects the arms 14 together. Also secured to the opposite sides of the frame of the 15 machine and projecting upwardly therefrom is a guide frame consisting of the guiding standards 18 each composed of spaced members and being connected together by the horizontal bar 18^a. The stop or push board 19 is mounted with its ends adapted to slide 20 between the spaced members of each standard 18. Cables 20 are connected with the member 19 near its ends, pass over pulleys 21 on the bar 18^a and are connected together 25 to form a single cable 20^a, the point of connection being located some distance from a sheave 22 supported at the upper end of one of the standards 18 and over which said cables also pass. The single cable 20^a leads 30 from the pulley 22 over a pulley 23 on the frame 1 and thence extends to a point of connection with an adjustable eye-bolt 24 on the lower end of the trip lever 25. The lever 25 is pivotally mounted on the frame 1, being 35 directly supported by a bracket 26, and the lower end of said lever is slotted longitudinally at 25' to admit of a certain amount of adjustment of the connection 24 whereby to control a slight variation in the timing of 40 the relative movements of the carriage 2 and stop or push board 19. On the bracket 26 is also mounted a trip arm 27 having a weight portion 27' at its lower end, the latter being engageable with the lug 25'' off-standing 45 from the lever 25.

It being noted that the upper end of the trip arm 27 is in the path of movement of the platen 5 before mentioned, the operation of the machine in conjunction with the improvements above described will be understood fully from the following description. We shall assume that the parts are in their full line positions as illustrated in Fig. 1, and that the lever 6 has just reached its illustrated position thereby causing the cutting wires 12 to cut the stick of clay previously fed onto the platen 5 into a series of bricks. On now moving the lever 6 to the right it will be apparent that the cut bricks which 50 have just previously been shifted from the platen 5 onto the spreader pallet 15, will be carried to the right, moving between and beyond the guide standards 18. At the beginning of the rightward stroke of the lever 6, however, the platen 5 impinges with the

trip arm 27, tilting said arm and with it the interlocked lever 25, to the dotted line position shown in Fig. 1 and in Fig. 3. Such movement of the lever 25 exerts a pull on the cables 20^a and 20 and elevates the stop or push board 19 just before the bricks reach the same, thereby permitting the bricks to pass on beneath said board until they are beyond the same or substantially in the full line position in which they are shown at α 75 in Fig. 1. On reversing the movement of the lever 6 carrying it leftward it will be apparent that the bricks just spread and resting on the pallet 15 will be swept from said pallet by the stop or push board 19, 80 owing to the fact that the latter is dropped at the end of the rightward stroke of the lever 6 at which time the platen 5 has assumed the position shown in dotted lines in Fig. 3, permitting the restoration of the 85 parts 25 and 27 to their normal vertical position. Thus it is that as the lever 6 starts to move leftward with the carriage 2 and supported parts the outer edge of the platen will simply strike the weighted arm 27 and 90 tilt the same without affecting in any way the position of the lever 25 and the stop board 19 connected with the latter. During this leftward movement of the lever 6 and the carriage 2 the action of the stop board 19 95 on the bricks transfers the latter, of course, to the portable pallet 16 ready to be carried off on said pallet, either manually or otherwise.

Having thus described the invention, what 100 is claimed as new is:

1. In a brick handling machine of the class described, the combination of a back and forth movable carriage, operating means for said carriage, means for supplying brick to 105 the carriage, a stop board movable into a position out of the path of movement of the brick when the carriage is moved in one direction and adapted to engage the brick as the carriage is moved in an opposite direction to transfer said brick to a suitable point of deposit, and means for controlling the movement of said stop board comprising a trip lever and co-acting trip arm mounted independently of and operable from the 110 carriage in its movement.

2. In a brick handling machine of the class described, the combination of a back and forth movable carriage, operating means for said carriage, means for supplying brick 120 to the carriage, a stop board movable into a position out of the path of movement of the brick when the carriage is moved in one direction and adapted to engage the brick as the carriage is moved in an opposite direction to transfer said brick to a suitable point of deposit, means for controlling the movement of said stop board comprising a trip lever mounted independently of the carriage, and a trip arm having interlocking relation 125 130

with respect to said lever and engageable by the carriage to impart movement to the lever.

3. In a brick handling machine of the class described, the combination of a back and forth movable carriage, operating means for said carriage, means for supplying brick to the carriage, a stop board movable into a position out of the path of movement of the brick when the carriage is moved in one direction and adapted to engage the brick as the carriage is moved in an opposite direction to transfer said brick to a suitable point of deposit, means for controlling the movement of said stop board comprising a trip lever mounted independently of and operable from the carriage in its movement, a trip arm having interlocking relation with respect to said lever and engageable by the carriage to impart movement to the lever, and a common axis for the trip arm and lever.

4. In a brick handling machine of the class described, the combination of a back and forth movable carriage, operating means for said carriage, means for supplying brick to the carriage, a stop board movable into a position out of the path of movement of the brick when the carriage is moved in one direction and adapted to engage the brick as the carriage is moved in an opposite direction to transfer said brick to a suitable point of deposit, means for controlling the movement of said stop board comprising a trip lever mounted independently of and operable from the carriage in its movement, a trip arm coöoperating with the lever to actuate the latter and arranged in the path of movement of the carriage for direct impingement by the latter, and a connection intermediate the lever and arm whereby said parts move together in one direction and are susceptible of movement one independently of the other in an opposite direction.

45 5. In a brick handling machine, the combination of a carriage and its operating

means, a stop board associated with the carriage and movable into and out of the path of brick supported on the carriage, and means to control the movement of the said stop board comprising an operating member connected with the stop board and a trip member operable from the carriage to actuate said operating member and movable independently of the operating member so that the latter may remain inactive under certain conditions of service.

6. In a brick handling machine, the combination of a carriage and its operating means, a stop board associated with the carriage and movable into and out of the path of brick supported on the carriage, an operating mechanism to control the movement of the stop board including a lever, a connection between the stop board and the lever, and means intermediate the carriage and said lever for actuation of said lever when the carriage moves in one direction and not affecting the action of the lever when the carriage moves in the opposite direction.

7. In a brick handling machine, the combination of a movable brick supporting carriage, means to operate the same, a stop board associated with the carriage and movable into positions in and out of the path of bricks supported on the carriage, and means to control positioning of the stop board including a member operable from the carriage to move the stop board into a predetermined position as the carriage moves in one direction, and means intermediate said member and the carriage establishing the coöperation of the carriage and member aforesaid whereby on movement of the carriage in another direction said member may remain inactive.

In testimony whereof I affix my signature in presence of two witnesses.

EDMUND GURNEY.
